UNITED STATES PATENT OFFICE.

WILLIAM T. LINTNER AND JAMES T. DOWDALL, OF GLOVERSVILLE,
NEW YORK.

DESIGN FOR A GLOVE OR SIMILAR ARTICLE.

SPECIFICATION forming part of Design No. 29,910, dated December 27, 1898.

Application filed November 12, 1898. Serial No. 696,814. Term of patent 14 years.

To all whom it may concern:

Be it known that we, WILLIAM T. LINTNER and JAMES T. DOWDALL, citizens of the United States, residing at Gloversville, in the county of Fulton and State of New York, have invented and produced a new and original Design for Gloves, of which the following is a specification, reference being had to the accompanying drawings, forming part thereof.

Figure 1 is a plan view of the back of a glove, showing three rows of our new design applied thereto; and Fig. 2 is a view of a portion thereof enlarged.

As shown in the drawings, the leading or material feature of the design consists of a plain raised rib or drawer *a*, and rows of zigzag or staggered stitching *b b* on each side of this raised rib or draw, the said rib or draw being left plain—that is to say, without stitching. On the glove shown in Fig. 1 three sep-

rate converging rows of such design are shown; but it is apparent that this design—to wit, a plain raised rib or draw and rows of zigzag or staggered stitching on each side of this raised rib or draw—is also applicable 25 to other leather goods and may be applied in single rows or in several rows.

Having described our invention, what we claim as new, and desire to secure by Letters Patent, is—

The design for a glove or similar article as herein shown and described.

Signed at Gloversville, in the county of Fulton and State of New York, this 10th day of November, A. D. 1898.

WILLIAM T. LINTNER.
JAMES T. DOWDALL.
